US0D1082440S

(12) **United States Design Patent** (10) **Patent No.:** **US D1,082,440 S**
(45) **Date of Patent:** **** Jul. 8, 2025**

(54) **CONTAINER ACCESSORY**

(71) Applicant: **YETI Coolers, LLC**, Austin, TX (US)

(72) Inventors: **Dustin Bullock**, Austin, TX (US);
Andy Bondhus, Austin, TX (US);
Steve Charles Nichols, Austin, TX
(US); **Walter T. Blanchard**, Manor, TX
(US)

(73) Assignee: **YETI Coolers, LLC**, Austin, TX (US)

(**) Term: **15 Years**

(21) Appl. No.: **29/841,440**

(22) Filed: **Jun. 6, 2022**

2,101,337 A 12/1937 Komenak
2,109,928 A 3/1938 Passalaqua
2,183,121 A 12/1939 Levine

Primary Examiner — Kelley A Donnelly

(74) Attorney, Agent, or Firm — Banner & Witcoff, Ltd.

(57) **CLAIM**

The ornamental design for a container accessory as shown and described.

DESCRIPTION

FIG. 1 is a front perspective view of a container accessory showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the container accessory form no part of the claimed design.

1 Claim, 5 Drawing Sheets
